UNITED STATES PATENT OFFICE.

ROBERT H. STROTHER, OF MONTCLAIR, NEW JERSEY, ASSIGNOR TO REMINGTON TYPEWRITER COMPANY, OF ILION, NEW YORK, A CORPORATION OF NEW YORK.

TYPE-WRITING MACHINE.

1,116,156.

Specification of Letters Patent.

Patented Nov. 3, 1914.

Application filed August 11, 1913. Serial No. 784,118.

To all whom it may concern:

Be it known that I, ROBERT H. STROTHER, a citizen of the United States, and resident of Montclair, in the county of Essex and State of New Jersey, have invented certain new and useful Improvements in Type-Writing Machines, of which the following is a specification.

My invention relates to typewriting machines and more particularly to the ribbon vibrator mechanism of such machines.

My invention has for its principal object to improve the means in such mechanism for controlling such mechanism for the purpose of doing mimeograph work.

The present invention is, in a sense, an improvement on that set forth in my prior Patent No. 1,046,893, dated December 10, 1912, said improvement consisting principally in providing means whereby, when the mechanism is set for stencil or mimeograph work, the operation of the printing keys causes the ribbon to be pulled away from printing position and below normal position, moving in a direction the reverse of the usual direction. This makes it possible to have the normal position of the ribbon not very far removed from the printing line and at the same time to leave a better and safer distance between the upper edge of the ribbon and the printing line when the ribbon is not used.

To the above and other ends, my invention consists in certain features of construction and combinations and arrangements of parts, all of which will be fully set forth herein and particularly pointed out in the claims.

In the accompanying drawings I have shown my invention applied to a Remington No. 10 or No. 11 typewriter, although the invention is applicable to typewriting machines generally.

In the drawings, Figure 1 is a rear elevation, partly in transverse vertical section, of a Remington typewriting machine having my invention embodied therein, only so much of said machine being shown as is necessary to an understanding of the application of my invention thereto. Fig. 2 is a rear elevation on a larger scale than Fig. 1, and Fig. 3 is a top plan view on the same scale as Fig. 2, of the ribbon vibrator and the parts immediately associated therewith, the mechanism being shown set for mimeograph work and in the position it occupies

when a key is depressed. Fig. 4 is an isometric view of the lever mechanism on a scale still larger than that of Fig. 2. Fig. 5 is a similar view of the lever mechanism of another form of the invention.

The Remington machine has a main frame comprising a base part 1, corner posts 2 and a top plate 3 which supports rails for the carriage, which carriage is not shown but it has mounted in it a platen 4, indicated in broken lines in Fig. 1. The platen is not carried directly by the carriage truck but is mounted in a shiftable platen frame having a wheel that rides on a shift rail 5, which rail is supported by upright posts 6, which posts are rigidly mounted at their lower ends on a shift bar 7 beneath the top plate, and said bar is in turn supported by posts 8 pivoted at their lower ends to the rear ends of shift key levers 10 mounted in the base of the machine.

I have not deemed it necessary to show in detail the shift key mechanism as it is well known in the art and as it can be of any suitable character, as far as my invention is concerned.

The machine comprises a set of front-strike type bars mounted on the front face of a segment 11, which segment is supported from the top plate of the machine. Said type bars are operated by printing key levers 12 which act on said type bars through trains of connections that are not shown herein but which are well known in the art. Said key levers when depressed act on a universal bar 13 suspended by wires 14 from arms 15 projecting toward the rear from a rock shaft 16 pivoted at 17 in the base of the machine. Said universal bar has an arm 18 projecting rearward therefrom and connected by means of a link 20 with carriage escapement mechanism not shown. Said arm 18 is also acted on by a returning spring 21 connected at its lower end to said arm and at its upper end to the segment 11.

The ribbon 22 is wound on spools 23 mounted on shafts 24 suitably supported in the stationary framework, said ribbon being led upward from said spools over stationary guides 25 and from one of said guides to the other through a ribbon vibrator 26, which has a long stem, the lower part of which is guided for up and down movement in a bracket 27 secured to the rear face of a frame-plate 28 having the form of a seg-

ment of a circle and secured by screws 30 to the type bar segment 11. The stem of the vibrator 26 has a button or headed stud 31, projecting rearward therefrom by means of which said vibrator is operated.

5 The means for operating the vibrator comprises a lever 32 which is pivoted on a screw 33 secured in a bifurcated bracket 34, which bracket is mounted on the rear face of the plate 28. In order to guide the lever 32 said lever, which is stamped out of sheet metal, is formed of two branches connected by a yoke piece 35, said branches being pivoted on the screw 33. Another lever 36 is pivoted to the lever 32 scissors fashion between the pivot and the end of said lever 32, on a pin 37; and said lever 26 is forked to form an open slot 38 which embraces the stud 31 on the ribbon vibrator. The lever 36 is connected by means of a link 39 with an arm 40 projecting rearward from the rock shaft 16. The action of the two levers 32 and 36 is controlled by means of two stops 41 and 42 mounted on or forming part of a slide 43 which is mounted by means of screws 44 on the rear face of the shift bar 7, said screws 44 passing through horizontal slots 45 in the bar 43. Said bar at one end has a long vertical slot 46 in which a pin 47 projects from an arm 48, which arm is rigidly mounted on the rear end of a rock shaft 50 having a milled head 51 on the front end thereof and in position to be readily manipulated. The rock shaft 50 is pivoted in any suitable way, as for example in a bracket 52 projecting from the front post 2, and another bracket 53 mounted on the type bar segment 11. The construction is such that when the milled head 51 is turned the slide or bar 43 is moved to the right or left. Said bar is yieldingly held in any one of three positions by means of a detent roller 54 mounted on the free end of a flat spring 55 secured 40 by screws 56 to the under side of the shift bar 7, said roller engaging three notches 57, 58 and 59 in the under side or edge of the bar 43. The stops 42 are preferably made adjustable in an up and down direction and to this end the stops are shown as made of separate pieces secured to the bar 43 by means of screws 60 passing through elongated slots 61 in said stops and threaded into the bar 43. The stops themselves consist each of a piece of sheet metal bent at right angles, the horizontal part of the stop being the part that is acted on by the mechanism.

50 The general principle of the mechanism thus far described is identical with that set forth in my prior patent above referred to. At each key stroke a definite extent of relative motion is imparted to the two levers 32 and 36, which is variably distributed between the levers by the stops 41, 42; and by

moving, said stops out of operation, the ribbon is not raised to printing position.

The upper end of the link 39 normally stands either exactly in the same vertical plane as the pivot 33 or near enough so for practical purposes; and in the present instance it stands about co-axially with said pivot. This is in order that when the shift rail 7 is shifted up and down the link 39 does not have any effect on the levers 36 to which it is connected, as the levers 36 and 32 are both at liberty to move up and down at their free ends by turning about the pivot 33 in one instance and by turning about the link 39 as a center in the other instance, with the result that the mechanism acts substantially the same in the upper and lower case positions. When the slide 43 is so adjusted that one of the stops 41-42 is in the path of the lever 32 and when a key is depressed, the rocking of the universal bar pulls down on the link 39, which has the effect of moving downward the pivot 37, which pulls down on the lever 32 until the free end of said lever is arrested by one of the stops. This lever then becomes fixed in position and the pivot 37 becomes a fixed pivot about which the lever 36 acts as a lever of the first order, moving the vibrator up until the head of the stud 31 is arrested by the under side of the stop 41 or 42, as the case may be. The link 39 has enough motion to bring the free end of the lever 32 into engagement with the upper surface of one of the stops and the stud 31 into engagement with the under surface of the same stop, and it will do this wherever said stop happens to be situated in the space between the normal positions of the lever 32 and of the stud 31. The ribbon will therefore be thrown to its full height if the stop 42 is in operative position and will be thrown to a less height if the stop 41 is in operative position. The stop 42 is in operative position when the detent 54 is in engagement with the notch 57, the stop 41 is in operative position when said detent engages the notch 58 and both of said stops are out of range of the cooperating parts and are out of operation when the detent 54 is in engagement with the notch 59; and it is in this last position that the parts are shown in the drawings. In this position of the parts, when a key is operated the lever 32 does not meet with any obstruction at all; and the entire stroke of the key is expended in pulling down said lever, as shown in Fig. 2, without moving the vibrator upward at all. It is the main purpose of the present improvements not only to avoid moving the vibrator upward at this time but actually to move it downward. To this end the lever 36 is prolonged beyond the stud 31, and in the present instance this is brought about by prolonging the lower of

the two branches between which the slot 38 is situated. Said lower branch is formed or provided with an extension 62 of substantial length, which extension, when the parts are 5 in the position shown in the drawings, preferably rests on a fixed stop here shown as consisting of a pin 63 projecting rearward from the type bar segment 11. The effect of this construction is that the lever 36, including its extension 62, acts when doing 10 stencil work, not as a lever of the first order, but as a lever of the second order having the pin 63 for a fulcrum, so that the stud 31, and with it the ribbon vibrator, are 15 moved downward instead of upward when a key is depressed, thus leaving ample room for the type 64 above the top of the ribbon, as indicated in Fig. 2.

In order to cause the ribbon mechanism, 20 including the vibrator and the levers 32 and 36, to move up and down ordinarily with the shifting of the platen, a shelf or bracket 65 is mounted as by rivets 66 on the front face of the stop bar 43 in such position 25 that when either of the stops 41, 42 is in operative position this shelf lies just beneath the stud 31 and supports said stud. The result is that when the rail 7 is shifted upward said stud, when the vibrator and the 30 levers 32 and 36 are all moved upward with the platen and to the same extent, as are also the stops 41 and 42. The ribbon is thus moved to the same position with relation to the platen whether said platen is in up- 35 per or lower case position. In order to insure that the stud 31 shall ride up on the shelf 65 when the bar 43 is moved from the position shown in the drawings to bring one of the stops 41 or 42 into operative position, 40 said shelf is formed with an incline or cam part 67 adapted to cam the stud upward if necessary.

In Fig. 5 I have shown a form of the present invention somewhat different from that 45 in the other figures, and more nearly resembling the form shown in my prior patent hereinbefore referred to. In this form of the invention the screw 33 is replaced by two short studs 331 and 332 and a lever 50 361 is pivoted by means of trunnions 371 between the branches of the lever 32, said lever 361 being a straight lever having its shorter arm lying between the two branches of the lever 32, where a link 391 is pivoted thereto at 392. The lever 361 has a notch or slot 381 like the notch 38 and it has an extension 621 like the extension 62 but in this instance the extension 621 rests, not on the fixed pin 63, but on the shift rail 7. In this 55 construction, therefore, the lever 361 moves up and down with the shift rail 7, and the vibrator moves up and down also, but to a less extent than the shift rail. With this 60 form of the invention when one of the stops 41 or 42 is in operation the ribbon has to

be lifted by the key stroke from a little lower initial position, relatively, when the parts are in the upper case position than when they are in lower case position, and the ribbon shifts up and down with the 70 platen when the parts are set for mimeographing, as well as when they are set for printing with the ribbon. It is in this mainly that the advantage resides in using the fixed pin 63 and shelf 65 because then 75 the ribbon shifts up and down with the platen when said ribbon is being used for printing, but when the parts are being used for mimeographing the ribbon does not shift up and down. The means whereby 80 this function is brought about, namely, that the vibrator and its accompanying parts shift up and down with the platen when the ribbon is in use for printing and when the parts are set for mimeograph work said vibrator 85 does not shift with the platen, is not of my invention but is an improvement added to my mechanism by others.

The form of the invention shown in my prior patent and also the form shown in 90 Fig. 5 of the present case, has, when applied to the Remington typewriter the disadvantage that, the short arm of the lever 361 being situated between the branches of the lever 32, it is necessary to put a right- 95 angled bend 393 in the link 391 in order to make said link clear certain parts of the mechanism. The upper part of said link extends nearly horizontally toward the front of the machine, in order to reach in to the 100 lever 361. This form of the link interferes with its rigidity in ordinary use and also makes the link liable to get sprung and thus change its effective length. In the form of the invention shown in the other figures of 105 the drawings this disadvantage has been obviated by a change in the shape of the lever 36, which lever is made with two branches connected by a yoke piece 68 which lies beneath one of the branches of the lever 32, thus throwing the short arm of the lever 36 clear outside of and at the rear of the bracket 34, as clearly shown in Fig. 4. The pivot 37 consists of a pin and the several 110 parts are separated by three sleeves or washers 69 strung along said pin. It will be perceived that both the levers 32 and 36 are thus provided with wide bearings, and the short arm of the lever 36 being thus moved out toward the rear makes it possible 115 to use a straight link 39 instead of one having the bend referred to. In my prior patent I showed a spring acting on the lever which in that patent corresponded to the lever 36 or 361 of the present case. 120 That spring was not absolutely essential in the form of the invention shown in the patent but it is rendered altogether unnecessary by the change just above described which 125 makes possible the use of the straight link 130

39, which has enough rigidity to push the parts back to normal position by the energy of the returning spring 21 of the universal bar.

5 The majority of users of typewriters have more work to do that involves the use of the ribbon than they have stencil work, and for this reason the tooth that separates the notches 58 and 59 in the bar 43, is made 10 longer than that between the notches 57 and 58 so that it requires a slight extra effort on the finger wheel or knurled head 51 to force the bar 43 into mimeographing position and a comparatively easy effort to 15 shift it back and forth between the two printing positions.

It will of course be understood that the setting of the slide 43 for writing on the upper or lower fields of the ribbon is useful 20 both in case the ribbon has two colors and also in case it is of one color, in the latter instance the change being made for the sake of using up a greater part of the surface of the ribbon. It will of course also be understood 25 that more than two stops like the stops 41 and 42, can be provided if preferred, so as to use up the surface of a one color ribbon even more completely.

Various changes can be made without departing from my invention.

What I claim as new and desire to secure by Letters Patent, is:—

1. The combination of printing keys, a pair of levers joined together, means operated by said keys for imparting to said levers a definite extent of relative turning movement about their point of juncture, variable stopping means for arresting said levers in a definite relative position, a ribbon vibrator operated by said levers, an extension on one of said levers, and a fulcrum for said extension, said stopping means being capable of an adjustment to an inoperative position and said lever in that case 45 turning about said fulcrum and causing said vibrator to be moved away from the printing point.

2. The combination of printing keys, a floating lever, a ribbon vibrator connected 50 with said lever, between the ends of the latter, a second lever to which said floating lever is pivoted, and variable stopping means for said levers for causing the vibrator to be moved to different extents to bring different fields of the ribbon to printing position and said stopping means being also capable of being thrown out of operation, said floating lever then acting as a lever of the second order to cause said vibrator to move away from printing position.

3. The combination of printing keys, two parts, connections between said parts and

to said keys whereby said parts are operated by said keys and said connections being such that the sum of the motions of said two parts at a key stroke is substantially constant, one of said parts moving toward and the other away from printing position, a ribbon vibrator operated by the first of 70 said parts, variable stopping means for variably distributing the relative motion between the two said parts, said stopping means being capable of being thrown out of operation, and means whereby when said 75 stopping means are out of operation said first part is caused to move the vibrator away from printing position at a key stroke.

4. The combination of printing keys, a ribbon carrier, vibrating means therefor 80 comprising two connected levers, a stop adapted to be interposed between said levers and to be withdrawn from between said levers, and an extension on one of said levers adapted when said stop is withdrawn 85 to cause said vibrator to move away from the printing point when one of said keys is operated.

5. The combination of a ribbon vibrator, a lever having said vibrator connected therewith between the ends of said lever, operating means at one end of said lever, a movable pivot for said lever between said operating means and said vibrator, and means capable of holding said pivot against 95 movement or not as desired, said lever, when said pivot is held against movement acting as a lever of the first order to move the ribbon to printing position and when said pivot is not held against movement said 100 lever acting as a lever of the second order to cause the ribbon to move away from the printing position.

6. The combination of a ribbon vibrator; two levers pivoted together scissors fashion, 105 and the first of said levers connected with said vibrator and having an extension beyond said vibrator; operating means connected with the other end of said first lever; a pivot for the second lever; and variable 110 stopping means for said second lever, said stopping means capable of being thrown into and out of operation; the construction being such that when said stopping means are in operation the ribbon is moved 115 to printing position and when said stopping means are out of operation the ribbon is moved away from printing position.

Signed at the borough of Manhattan, in the county of New York, and State of New 120 York, this 9th day of August, A. D. 1913.

ROBERT H. STROTHER.
